UNITED STATES PATENT OFFICE.

WILLIAM H. MILLER, OF SOUTH BEND, INDIANA.

SPRINKLING-HEAD FOR STREET-SPRINKLERS.

SPECIFICATION forming part of Letters Patent No. 520,693, dated May 29, 1894.

Application filed September 13, 1893. Serial No. 485,385. (No model.)

To all whom it may concern:

Be it known that I, WILLIAM H. MILLER, of South Bend, in the county of St. Joseph and State of Indiana, have invented certain new 5 and useful Improvements in Sprinkler-Heads for Street-Sprinklers; and I do hereby declare that the following is a full, clear, and exact description thereof, reference being had to the accompanying drawings, and to the letters 10 and numerals of reference marked thereon, which form part of this specification.

This invention is an improvement in sprinkling heads for street sprinkling machines, and its object is to so construct the head that 15 it can be readily and expeditiously cleansed when desired, its interior being easily accessible without disturbing the valves. Also to divide the head into two or more chambers, respectively provided with jet apertures of 20 different sizes, and with separate inlet valves, so that streams of different volumes can be discharged from the head at the will of the driver of the machine, and according to the character of the surface being sprinkled; and 25 the jet openings are so arranged (preferably) that the water will be ejected in vertical sheets, or planes at right angles to the machine, instead of in horizontal planes.

The invention therefore consists in the novel 30 construction and combination of parts hereinafter described and claimed.

Figure 1 is a perspective view of a street 35 sprinkling machine with my improved sprinkler heads attached. Fig. 2 is a perspective view of the sprinkler head detached. Fig. 3 is a transverse sectional view thereof, indicating the head opened by the aid of dotted lines. Fig. 4 is a longitudinal sectional view thereof.

40 In the drawings, A represents a valve chamber, or box, communicating through a pipe B with the tank of the machine to which the sprinkler head is attached. This box is of any suitable construction, and is provided 45 with two openings a, a', in its bottom, which are closed by valves C, C', seated against annular valve seats c, c', fitted in openings a, a', respectively. The valves are provided with stems C² which play through stuffing boxes C³ 50 secured to the top of box A and springs C⁴ interposed between the bushings C³ and the valves normally hold the latter closed. The

valves may be independently operated by means of levers and connecting rods not shown, that extend to the seat of the driver 55 at the front part of the machine and can be arranged to be worked in the ordinary manner either by hand or foot.

The sprinkler head D is almost cylindrical and is closed at both ends, but open at top, 60 its open side being adapted to fit neatly and closely to the bottom of box A as shown in drawings. At one side of the head a hinge rod E is secured between projecting ears d', and the box A is provided with hook shaped 65 ears A² on the lower edge of its rear side, which are adapted to receive the ends of rod E, as indicated in Fig. 2, thereby suspending the head on the box, and hinging it thereto by a loose or detachable hinge joint, for when 70 the head is swung down and back from under the box it can be raised so as to disengage rod E from ears A², and be thus detached from the box. On the front side of the head, opposite ears d', are ears d, between which is 75 pivoted the end of a rod F, having a thumb nut f on its free end, and when the head is closed, as indicated in Figs. 1 and 2, the free end of said rod is swung up between ears A³ on the front upper edge of the box A, and nut 80 f screwed down, so as to lock the rod and draw the head closely against the bottom of the box, as indicated in the drawings. A packing G of rubber or other suitable material is secured to the lower face of the box so 85 that when the head is closed as indicated in Fig. 2 a practically water tight joint is made between them.

The head is divided by a transverse partition D', into two chambers 1 and 2, one below 90 each opening a, a', respectively, so that water can be admitted into the chambers independently by unseating valve C, or C'. The lateral or side walls of the head are perforated as shown, the perforations being more numerous at the outer and upper side of the head (adjoining rod F) than at the rear side, and furthermore the perforations for chamber 1 are larger than those for chamber 2. In practice the sprinkling will generally be done 95 from only one chamber at a time, and the different diameters of the perforations enable the driver to vary the quantity of water ejected according to the requirements of the sur-

face being sprinkled. It will furthermore be observed that the water escapes in vertical planes through the perforations in the head, and will sprinkle a narrow strip transversely 5 of the machine as it is driven forward, thus obviating the annoyance incident to the employment of sprinklers using a horizontal discharge, by which the water is spread toward the sides and rear of the machine and apt to 10 wet anything passing near to the rear of the apparatus, while my sprinklers having a vertical discharge will not throw water either in advance of, or behind, the sprinkler head.

Within each chamber 1 and 2, is arranged 15 a diaphragm H, consisting of a curved plate, pivoted between the end walls of the chambers as indicated at h Figs. 3 and 4 so that it can be swung up to the position indicated in dotted lines Fig. 3. When the head is unclosed 20 these partitions underlie the valves, and receive the impact of the incoming water when the valves are opened and serve to divert the water so that it escapes with most force through the uppermost openings at the outer 25 side of the chamber, while part of the water will escape around the end of the diaphragm and through the bottom and rear perforations in the head, with much less force however. In order to permit the lower end of the dia- 30 phragm to be raised the head is provided with a horizontal ledge or flange D² at its rear upper side as indicated in the drawings, against which the upper ends of the dia- 35 phragms press when the head is in operative position. As shown and described, the head is practically double, each part being pro- 40 vided with its own valve, so that it can be used independently, obviously however the head might have but one chamber, or more than two. To clean the head, rod F is loosened 45 and the head dropped into the position shown in dotted lines Fig. 2, (the water being re- 50 tained in box A by the valves therein,) and the diaphragms H are turned up thus render- 55 ing every part of the head accessible. If desired the head can be lifted from the box and after it is cleansed it is again hung upon ears A², the diaphragms H drop into position by gravity, rod F is swung into place and se- 60 cured, and the machine is ready for operation.

The detachability of the sprinkler head without disturbing the valves, or employing any tools, loosening of bolts, &c., and the ease with which it can be replaced, is of great 65 practical advantage in this class of machines.

Having thus described my invention, what I claim as new, and desire to secure by Letters Patent thereon, is—

1. The combination of the head having lateral discharge perforations, with a curved dia- 70 phragm pivoted in said head, substantially as described.

2. The combination of the hinged sprinkler head, with the curved diaphragm pivoted in 75 said head, substantially as specified.

3. The combination of the valve box, com- 80 municating with a water supply, with a sprink-

ler head detachably hinged to and below said box, and a water deflecting diaphragm in said head, substantially as set forth. 70

4. The combination of the valve box communicating with a water supply and the valve therein; the perforated sprinkler head detachably hinged to and below said box, and the deflecting partition pivoted in said head, sub- 75 stantially as and for the purpose described.

5. The combination of the valve box and the valve therein, with the chambered sprinkler head detachably hinged to and beneath said box, having a series of perforations in 80 its sides for discharging water and deflecting diaphragms in each chamber, substantially as and for the purpose specified.

6. The combination of a sprinkler head per- 85 forated to discharge the water and hinged to a water supply, with a deflecting diaphragm pivoted in said head, substantially as and for the purpose set forth.

7. The combination of the valve box and the independent valves therein, with the single 90 sprinkler head detachably hinged to said box having separate chambers communicating with the respective valve openings in the box, and provided with discharge openings of dif- 95 ferent size, respectively, substantially as de- scribed.

8. The combination of the valve box, the sprinkler head detachably hinged thereto and thereunder, and provided with openings for the discharge of water, with a curved deflect- 100 ing plate pivoted in said head, substantially as specified.

9. The combination of the sprinkler head having two chambers, provided with lateral 105 discharge openings of different relative size respectively, with a deflecting diaphragm piv- 110 oted in each chamber, and an independent water inlet to each chamber, substantially as set forth.

10. The combination of the valve box, the 115 sprinkler head detachably hinged thereto and thereunder, and provided with openings for the discharge of water, with a partition in said head, and a deflecting diaphragm in each chamber, substantially as described. 120

11. The combination of the valve box com- 125 municating with a water supply, the sprinkler head suspended beneath said box, and detachably secured thereto by a detachable or loose hinge joint at one side, and a pivoted 130 rod and locking nut at the other side, sub- stantially as specified.

12. The combination of the valve box com- 135 municating with a water supply, the sprinkler head detachably suspended beneath said box, and secured thereto by a detachable or loose hinge joint at one side, and a pivoted rod and locking nut at the other side, and a deflecting diaphragm pivoted in said head, substantially as set forth.

13. The combination of the sprinkler head D, having a flange D², with the pivoted dia- 140 phragm H, substantially as described.

14. The combination of the box A, and the

independent spring controlled valves therein; with the sprinkler head D having independent chambers 1 and 2, the loose hinge joint between one side of said head and the box, and the pivoted rod F and its locking thumb nut for securing the opposite side of the head to the box, the packing G interposed between the head and box, and the pivoted diaphragm in said chambers all constructed and arranged

to operate substantially as and for the purpose set forth.

In testimony that I claim the foregoing as my own I affix my signature in presence of two witnesses.

WILLIAM H. MILLER.
